CLAIM

The ornamental design for a cleaning tool, as shown and
described.

DESCRIPTION

FIG. 1 is a front, top, and right side perspective view of a
cleaning tool;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in FIG. 6 depict portions of the cleaning
tool that form no part of the claimed design.

1 Claim, 7 Drawing Sheets
